US0D1070921S

(12) **United States Design Patent** (10) **Patent No.:** **US D1,070,921 S**
(45) **Date of Patent:** **** Apr. 15, 2025**

(54) **MOCK ENGINE BLOCK**

(71) Applicant: **Speedway Motors, Inc.**, Lincoln, NE (US)

(72) Inventor: **Austin Drueke**, Lincoln, NE (US)

(73) Assignee: **Speedway Motors, Inc.**, Lincoln, NE (US)

(**) Term: **15 Years**

(21) Appl. No.: **29/914,829**

(22) Filed: **Oct. 23, 2023**

(51) **LOC (15) Cl.** **15-01**

(52) **U.S. Cl.**

USPC **D15/5**

(57) **CLAIM**

The ornamental design for a mock engine block as shown and described.

DESCRIPTION

FIG. 1 is a perspective view of the mock engine block.

FIG. 2 is a front view of the mock engine block.

FIG. 3 is a rear view of the mock engine block.

FIG. 4 is a left view of the mock engine block.

FIG. 5 is a right view of the mock engine block.

FIG. 6 is a top view of the mock engine block; and,

FIG. 7 is a bottom view of the mock engine block.

The broken lines shown in the views illustrate environmental subject matter only and form no part of the claimed design.

1 Claim, 7 Drawing Sheets
